AUTOMOBILE

William L. Mitchell, Birmingham, Mich., assignor to General Motors Corporation, Detroit, Mich., a corporation of Delaware

Filed May 2, 1962, Ser. No. 69,929

Term of patent 7 years

(Cl. D14—3)

FIGURE 1 is a side elevational view of an automobile, showing my new design, the other side of the automobile being the same.

FIGURE 2 is a front elevational view and

FIGURE 3 is a fragmentary top plan view.

The dominant features of my design reside in the full line portions of the drawings.

I claim:

The ornamental design for an automobile, substantially as shown and described.
